(57) **CLAIM**

We claim the ornamental design for a fetal head disimpactor, as shown and described.

DESCRIPTION

FIG. 1 is a perspective view of the new design of a fetal head disimpactor, according to a first embodiment;

FIG. 2 is a first side view of the new design of the fetal head disimpactor, shown in FIG. 1;

FIG. 3 is a second side view of the new design of the fetal head disimpactor, shown in FIG. 1;

FIG. 4 is a front view of the new design of the fetal head disimpactor, shown in FIG. 1;

FIG. 5 is a rear view of the new design of the fetal head disimpactor, shown in FIG. 1;

FIG. 6 is a top view of the new design of the fetal head disimpactor, shown in FIG. 1;

FIG. 7 is a bottom view of the new design of the fetal head disimpactor, shown in FIG. 1;

FIG. 8 is a perspective view of the new design of a fetal head disimpactor, according to a second embodiment;

FIG. 9 is a first side view of the new design of the fetal head disimpactor, shown in FIG. 8;

FIG. 10 is a second side view of the new design of the fetal head disimpactor, shown in FIG. 8;

FIG. 11 is a front view of the new design of the fetal head disimpactor, shown in FIG. 8;

FIG. 12 is a rear view of the new design of the fetal head disimpactor, shown in FIG. 8;

FIG. 13 is a top view of the new design of the fetal head disimpactor, shown in FIG. 8; and,

FIG. 14 is a bottom view of the new design of the fetal head disimpactor, shown in FIG. 8.

The broken lines shown in the figures depict environmental subject matter only and form no part of the claimed design.

1 Claim, 14 Drawing Sheets
